UNITED STATES PATENT OFFICE.

ANDRÉ F. GOBIN, OF BROOKLYN, NEW YORK.

AUXILIARY WATER HEATER.

Application filed May 18, 1926. Serial No. 109,838.

The invention relates, broadly, to improvements in water heaters and more specifically to improvements in water heaters of the type wherein a plurality of separate sources of heat are utilized to raise the temperature of the water.

In the ordinary water heater employing gas as the heating medium and wherein the water is fed into the heater in a cold condition, a considerable period of time ensues after the gas is lighted before the temperature of the water is raised to the desired point. The present invention aims to remedy the above defect and to make it possible to obtain large volumes of hot water in comparatively short time, which beneficial result is achieved by employing in connection with the heater means for maintaining the water therein in a preheated or initially warm condition. More specifically, the invention contemplates providing a heater in which a portion of the heating coils are surrounded with a jacket through which flows hot water from a furnace or other suitable and convenient source to keep the water within the said coils in a preheated condition and to enable it to be rapidly raised to the desired temperature when the gas is lighted.

The invention further resides in certain details of construction and arrangement of parts which will in part be obvious and in part be pointed out in the following description of the accompanying drawing in which the preferred embodiment of the invention is disclosed.

In the drawings:—

Figure 1 shows the invention employed in conjunction with the pre-heating means and the manner of connecting it to the hot water storage boiler.

Figure 2 is a view showing the heater partly in front elevation and with the door open, and partly in section and

Figure 3 is a sectional view of a detail of the heater.

In Figure 1, the improved water heater, 1, is shown in conjunction with the hot water storage boiler, 2, and the hot water furnace, 3. The cold water enters the storage boiler through the pipe line, 4, and hot water is drawn off from the top through the pipe 5. The cold water in the boiler, 2, enters the heater, 1, through the pipe, 6, is there heated, and hot water is delivered back into the boiler through the pipe, 7. It will be under-

stood that there is a continuous circulation of water through boiler, 2, pipe, 6, heater, 1, and pipe, 7. The hot water furnace, 3, is of ordinary and well-known construction but is provided with the pipes, 8 and 9, leading to the heater, 1, through which hot water from the furnace flows and serves to preheat the water in the heater in the manner hereinafter described. Leading to the heater, 1, is the gas pipe, 10, which is provided with a valve, 11, serving to regulate the flow of gas to the burner.

The nature of the heater is more clearly shown in Figure 2, to which reference will now be had. It comprises in general two compartments, housing water coils, 12, 13, the upper coils, 12 being subjected to the influence of the gas burner, 14 supplied through pipe, 10, and the lower coils, 13, being jacketed with hot water from the furnace, 3. The lower compartment is watertight and is separated from the upper compartment by any suitable means such as the plate 15. The upper compartment is provided with the door, 16, which is suitably hinged and allows ingress to the interior of the compartment for the purpose of inspection and in order that the burner, 14, may be lighted. The coils 12 and 13, are serially connected by means of any suitable watertight joint. The preferred form of this joint is shown in Figures 2 and 3 of the drawings. A bushing, 17, extends thru the plate and the ends of the coils 12 and 13, are rigidly secured therein by means of brazing material 19 in the manner shown in Figure 2. The nut 18 is threaded on the bushing and lends a neat appearance to the heater.

This form of joint I have found to be very effective. The coils, 12 and 13, in service are subjected due to their heated condition to severe strain and it is necessary that the joint connecting them be extremely secure as well as watertight. The brazed joint herein described subserves these purposes very well.

The coils 12 are composed of convolutions which vary in diameter as shown in Figure 2. This allows them to expand relative to one another when heated and prevents undue strain thereon due to their heated condition.

At the top of the gas chamber, there is provided a flue 20, the purpose of which is to conduct the burnt gases away. When the burner 14 is lighted, the flame and burnt

gases rise axially thru the coils 12, heating the same, and the burnt gases are omitted thru the flue 20.

In connection with the water jacket, attention is called to the fact that the pipe, 8, leading from the furnace may be connected either from the right as seen in Figure 2 and as shown therein or it may be connected from the left. For this purpose a plug, 21, is provided which may be removed and the pipe, 8, screwed in the opening thereof. In case it is desired to insert the pipe 8 from the left, the opening at the right will be plugged up. By this arrangement connections to the furnace may be easily and conveniently made.

In operation, the jacket surrounding the coils, 13, fed with hot water from the furnace, 3, maintains the water within the said coils in a preheated or warm condition so that when the gas heater 14, is lighted the temperature of the water is very quickly raised. The series connection of coils, 12 and 13 and the jacketing of the lower heating coils result in a good circulation of the water through the closed system including heater, 1, pipes 6 and 7 and storage boiler, 2. The design and location of the various elements are such as to obtain a maximum in thermal efficiency and result in a heater which is both efficient and economical.

It will be understood, of course, that either source of heat, the gas burner, 14, or the hot water jacket around coils, 13, may be used separately and independently of each other. If the furnace, 3, were not running

it would still be possible to obtain hot water by simply lighting burner, 14. And, conversely, hot water might be obtained without the necessity of lighting the burner, 14, by reason of the hot water jacket around coils, 13. The best and most efficacious results, however, are obtained with both the gas burner and jacket operating together.

Many modifications in the above described structure may be made without departing from the spirit of my invention and I desire to be limited only by the prior art and the scope of the claim.

What I claim is:

In a device of the character described, a pipe circuit comprising a plurality of coils of pipe arranged in series to conduct a fluid serially therethrough, said pipe circuit being divided into sections, a casing surrounding the coils of the pipe circuit, a partition dividing said casing into compartments, said partition having an opening through which the pipe extends and wherein abutting ends of the pipes comprising the sections are placed and meet, a watertight joint surrounding said ends in said opening, said joint serving to seal the abutting ends of the sections and the opening, means for supplying a heated fluid to one of said compartments and around the coils therein, and a burner within another of said compartments for heating the coils therein.

In testimony whereof, I have signed my name to this specification this fifteenth day of May, 1926.

ANDRÉ F. GOBIN.
